DESIGN FOR A GLOVE

William S. Hatch, Gloversville, N. Y.

Application February 5, 1937, Serial No. 67,461

Term of patent 3½ years

To all whom it may concern:

Be it known that I, William S. Hatch, a citizen of the United States of America, residing in Gloversville, county of Fulton, and State of New York, have invented a new, original, and ornamental Design for a Glove, of which the following is a specification, reference being had to the accompanying drawing, forming part thereof, wherein,

The characteristic feature of my design resides in the contrasting pipings on the glove, as shown.

I claim:

The ornamental design for a glove, substantially as shown and described.

WILLIAM S. HATCH.
